UNITED STATES PATENT OFFICE.

FREDERICK L. DORNBROOK, OF MILWAUKEE, WISCONSIN, ASSIGNOR TO ROBERT ROM,
OF MILWAUKEE, WISCONSIN.

SAFETY APPLIANCE FOR STEAM-BOILERS.

1,293,730.

Specification of Letters Patent. Patented Feb. 11, 1919.

Application filed October 16, 1916. Serial No. 125,937.

To all whom it may concern:

Be it known that I, FREDERICK L. DORNBROOK, a citizen of the United States, residing at Milwaukee, in the county of Milwaukee and State of Wisconsin, have invented new and useful Improvements in Safety Appliances for Steam-Boilers, of which the following is a full, clear, concise, and exact description, reference being had to the accompanying drawing, forming a part of this specification.

This invention relates to safety appliances for steam boilers.

In practice, steam boilers are commonly provided with tubes projecting therein to the lowest safe water level and equipped with fusible plugs whereby upon an abnormal drop in water level of the boiler with a consequent drainage of such tube the steam from the boiler passes into the tube and fuses the plug thereof thus finding an outlet to the atmosphere. Accordingly when the water level of the boiler is thereafter raised a new plug must be substituted for the used plug and such substitution has heretofore entailed a temporary shutoff of the tube, removal of the used plug, insertion of a new plug and reopening of the tube. Moreover, this method of substitution has incurred the risk of forgetfulness upon the part of the engineer to reopen the tube after insertion of the new plug.

The present invention relates more particularly to such safety appliances and has among its objects to provide a multiple plug appliance whereby one plug may be substituted for another by mere valve adjustment.

A further object is to provide an appliance insuring against the exclusion from service of any one plug without substitution of another.

Various other objects and advantages of the invention will hereinafter appear.

The accompanying drawing illustrates one embodiment of the invention and the same will now be described, it being understood that the invention is susceptible of embodiment in other forms falling within the scope of the appended claims.

50 In the drawing,

Figure 1 shows the appliance in vertical section and as attached to a boiler; and,

Fig. 2 shows a top plan view of said appliance.

55 The appliance comprises a casing 1 di-

vided into two chambers respectively provided with fusible plugs 2 and 3 and shutoff valves 4 and 5. The casing has an intake 6 and is shown as connected to a boiler 7 of ordinary type by a pipe section 8 threaded into its intake and into a plug 9 in the wall of said boiler, said plug having a pipe section 10 projecting into the boiler, whereby said pipe sections and casing form a tube of the character above mentioned.

More specifically describing the appliance, the casing has a partition 11 separating the plugs 2 and 3 and restricting the chambers formed thereby to communication with the intake 6 through a supply passage 12 in said partition. The partition is provided with openings from said passage into both chambers and with a tapered valve seat 13 surrounding each of said openings. Also, the partition is provided within and at the base 70 of the chambers with walls inclined toward said opening and preferably slightly curved for a purpose hereinafter set forth.

The valves are of like construction and each comprises a washer tapered at both 80 ends and circumferentially grooved intermediate of its ends. The two valves are respectively fixed to aligned threaded stems 14 and 15 and are respectively provided with operating handles 16 and 17 and extensions 85 18 and 19 coöperable to interlock said valves against simultaneous closure. Each stem has a threaded bearing 20 threaded into the casing and provided with the usual bonnet. Also, each bearing 20 is provided with a 90 tapered valve seat 21 for the rear end of its respective valve.

Thus assuming use of the appliance with the valves set as illustrated the plug 2 would be active while the plug 3 would be 95 excluded from service. That is to say, the boiler pressure would, under normal condition, force water from the boiler upwardly through the tube into the left hand chamber of the casing 1, while the flow of water to the right hand chamber would be shut off by the valve 5. Thus should the water level of the boiler drop abnormally with a consequent drainage of the tube the rising steam would be confined to contact with 105 the plug 2. Accordingly, after fusing of the plug 2 the plug 3 could be substituted therefor by merely opening the valve 3 and closing the valve 4. Thereupon the plug 2 could be replaced at the convenience of the 110

engineer for use alternately with plug 3. Moreover, when making such facile and expeditious substitutions the engineer would be relieved of all responsibility as to subsequent protection of the boiler for the interlocking extensions of the valves would insure the opening of the closed valve prior to closure of the other.

Again referring to the valves, it will be observed that when in open position for use of their respective plugs, they will bear against the seats provided therefor in their bearings 20. Accordingly, when the plugs fuse it will be impossible for any of the molten metal falling therefrom to contact with the threaded valve stems. Moreover, it will be observed that any molten metal falling upon the valves will tend to enter and follow the grooves therein and thus fall to the bottom of the plug chambers whereupon with the partition walls formed as described the same will wash into the piping of water column.

What I claim as new and desire to secure by Letters Patent is:

1. A fusible plug appliance for steam boilers comprising means providing a plurality of plug chambers having a common intake and shutoff means between each of said chambers and said intake whereby said chambers may be connected with said intake alternatively.

2. A fusible plug appliance for steam boilers comprising means providing a plurality of plug chambers having a common intake and shutoff means between each of said chambers and said intake whereby said chambers may be connected with said intake

alternatively, said shutoff means insuring connection of at least one of said chambers with said intake at all times.

3. In a fusible plug appliance for steam boilers in combination, a plurality of fusible plugs, means providing separate chambers for said plugs and valves for said chambers providing for use of said plugs alternatively.

4. In a fusible plug appliance for steam boilers in combination, a plurality of fusible plugs, means providing separate chambers for said plugs and valves for said chambers providing for substitution of one of said plugs for another and insuring opening of the chamber of the former upon closure of the chamber of the latter.

5. In a fusible plug appliance for steam boilers, in combination, a plurality of fusible plugs, means providing separate chambers therefor, and separately operable shutoff valves for said chambers whereby the said plugs may be used alternatively, said valves having interlocking means insuring open positioning of at least one of the same upon closure of the remainder thereof.

6. In a fusible plug appliance for steam boilers, in combination, a housing having an intake and being divided into separate plug chambers both communicable with said intake and separately operable valves for said chambers to close the same to said intake, said valves being aligned in an opposed relation and having parts coöperating to insure against simultaneous setting thereof in closed position.

In witness whereof, I have hereunto subscribed my name.

FRED L. DORNBROOK.
